CLAMPING TOOL

John C. Bluhm, Huntley, Ill.

Application June 10, 1933. Serial No. 675,276

6 Claims. (Cl. 81—78)

The present invention relates to an improved clamping tool of the combined plier and wrench type.

An essential feature of the invention is to provide a simple, economical and efficient clamping tool composed of a minimum number of parts and of sufficient power, strength and durability as to be capable of withstanding the exacting working conditions to which tools of this character are usually subjected.

A further object is to provide a combined plier and wrench with a double or divided pivotal fulcrum located at a point remote from the clamping jaws and which extends in a direction opposite to the jaws so as to obtain the maximum leverage and insure the jaws engaging the work with a firm and positive grip.

A further object comprehends the provision of a clamping tool in which the jaws may be readily adjusted to fit work of various kinds and sizes.

Other objects and advantages of the invention will become apparent from the following description when taken in conjunction with the accompanying claims and drawing.

25 Referring to the drawing, in which are shown preferred embodiments of the invention,

Figure 1 is a side view of the clamping tool with the parts shown in full lines in their closed position and in their opened position in dotted lines.

Figure 2 is a plan view of Figure 1.

Figure 3 is a side elevation of a modified form of the invention.

Figure 4 is a plan view of Figure 3; and

35 Figure 5 is a plan view of one end of the tool, showing a further modification.

Referring to the drawing, in which like numerals indicate like parts in the several views, the clamping tool comprises a pair of handle members 10 and 11 of substantially the same length. The member 11 may be serrated as at 12 to insure the tool being firmly gripped by the operator. The member 10 is preferably formed with an intermediate bent or curved arm 14 which 45 extends upwardly and outwardly, as shown in Figure 1, and terminates in the laterally disposed upper toothed jaw 15. The member 11 has an intermediate inclined substantially straight portion 16 which terminates in the laterally extending lower jaw 17, which may be provided with an opening 18 through which the arm 14 extends, so that the jaws will align and be moved into and out of their clamping positions.

55 The members 10 and 11 are connected by double or divided pivotal connection which may

be in the form of a pair of links 19 and 20 (Fig. 2), that are movably connected to the member 10 by the pin 21 and secured to the member 11 by the pin 22 at the juncture of the handle portion or shank with the inclined arm 16. Obviously a single link may equally be employed for pivotally connecting the members 10 and 11.

In order that the maximum leverage may be obtained and the jaws be moved into firm engagement with the work, the pivotal fulcrum is 65 connected to the member 10, so as to extend in a direction opposite to that of the jaws 15 and 17 and is located at points on the members 10 and 11 remote from the jaws.

The arm 14 of the member 10 is shaped to contact with the arm 16 of the member 11, in order that the jaws may be moved easily into and out of clamping engagement. Additionally, the arm 14 coacts with the inner wall of the opening 18 to limit the outward movement of the jaws when 75 the parts assume their open position, as shown in dotted lines in Figure 1.

In Figures 3 and 4, the invention is shown in the form of a wrench 23 having a handle portion 24 and an intermediate curved or bent portion 80 25, which may be reversely curved as at 26 to provide the substantially straight outwardly inclined arm 27 that terminates in the lower laterally disposed toothed jaw 28. A member 29 of shorter length than the handle 24 has its inner end 30 85 provided with a lug or shoulder 31 and a cut-out portion 41. The intermediate portion of the member 29 is bent upwardly to form the arm 32 which extends through an opening 33 in the lower jaw 28 and terminates in the laterally disposed upper jaw 34. The handle portion 24 is connected to the member 29 by a double pivotal connection 35, that is secured as at 36 to the member 29 and at 37 to the handle 24, so as to be positioned and to operate in substantially the same 95 manner as the link connection previously described. In order to normally maintain the jaws 28 and 34 in their closed position and also to insure that the work is firmly engaged by the jaws without manual pressure being exerted on 100 the member 29, a yieldable tensioning means is provided which may be in the form of a rod 38 secured at one end by a pin 39 to an intermediate portion of the pivotal connection 35. The opposite end of the rod 38 loosely extends into an 105 opening in the shoulder 31. A coil spring 40 surrounds the rod 38 and is confined between the shoulder 31 and the pin 39 normally to urge the jaws toward each other, so that when the jaws are opened and the spring compressed, the rod 110

may move axially through the opening. The cut-away portion 41 of the arm 29 is so positioned as to be conveniently engaged by the thumb of the operator, as he grasps the handle 24, so that 5 upon downward pressure being exerted on the cut-out portion 41, the jaws may be opened either to engage or be released from the work. The tension of the spring 40 is sufficient to maintain the jaws firmly in engagement with the work 10 and the power thereof may be varied in accordance with the particular kind of work with which the tool is used.

Instead of providing one of the arms of the tool with an opening for receiving the lower clamping jaw, there is shown in Figure 5 a construction 15 in which this opening is omitted and the intermediate arms 42 and 43 of the tool are shaped to cross or lap each other, so that the jaws 45 will be properly positioned to be brought 20 into and out of clamping engagement. The links 46 are pivotally connected to the handle portions 44 of the tool by the pins 47 and 48 in substantially the same manner as the link connection previously described, so that the tool is constructed 25 and operates similar to the form shown in either Figures 1 or 3.

It will be seen that by reason of the present invention, there is provided a clamping tool of the combined plier and wrench type in which the clamping jaws will be brought firmly and 30 positively into engagement with the work and in which the power and strength of the tool is materially enhanced due to the double pivotal connection being located at a point remote from the clamping jaws and extending in a direction 35 opposite to the jaws. Moreover, the increased leverage effected by the location of the pivotal connection relative to the jaws gives greater power and strength to the tool without weakening 40 the link connection at the weak points thereof, and thus obviates the necessity of providing additional strengthening means to take care of the increased pressure or strain exerted at such weak points.

45 It is to be understood that the forms of the invention herewith shown and described are merely illustrative of preferred embodiments and that such changes may be made as fall within the purview of one skilled in the art without departing from the spirit of the invention and the scope of the appended claims.

I claim:

50 1. A tool of the class described including upper and lower clamping members, the lower member having an intermediate curved arm terminating in a laterally disposed upper jaw, the upper member having a handle portion and an intermediate laterally inclined arm crossing the curved arm of the lower member and terminating in a lower 55 jaw in alignment with said upper jaw, and a linked connection between said members, said connection being pivotally secured to the upper member adjacent the inclined arm thereof and pivotally secured to the arm of the lower member at a point below the upper member.

60 2. A tool of the class described including upper and lower clamping members, the upper member having a handle portion at one end and an intermediate inclined arm terminating in a laterally disposed toothed jaw, said jaw having an 65 opening therein, the lower member having an intermediate curved arm extending through said opening and terminating in a laterally disposed toothed jaw in alignment with and above said

first-mentioned jaw, and a linked connection between said members, said connection being pivotally secured to the upper member adjacent its inclined arm and pivotally secured to the arm of the lower member at a point below the upper 80 member.

3. A tool of the class described including upper and lower clamping members, the lower member having an intermediate curved arm terminating in a laterally disposed upper jaw, the upper member having a handle portion and an intermediate laterally inclined arm crossing the curved arm of the lower member and terminating in a lower jaw in alignment with said upper jaw, a linked connection between said members, said connection being pivotally secured to the upper member adjacent its inclined arm and pivotally secured to the arm of the lower member at a point below the upper member, and yieldable means confined between and connected to said link connection and one of said members for normally maintaining the jaws in their closed position. 85

4. A tool of the class described including upper and lower clamping members, the lower member having an intermediate curved arm terminating in a laterally disposed upper jaw, the upper member having a handle portion and an intermediate laterally inclined arm crossing the curved arm of the lower member and terminating in a lower jaw in alignment with said upper jaw, a linked connection between said members, said connection being pivotally secured to the upper member adjacent its inclined arm and pivotally secured to the arm of the lower member at a point below the upper member, said lower member having a shoulder thereon, and yieldable means confined between and connected to said link connection and said shoulder for normally maintaining the jaws in their closed 100 position. 105

5. A tool of the class described including upper and lower clamping members, the upper member having a handle portion at one end and an inclined arm terminating in a laterally disposed lower jaw, said lower member being shorter than the upper member and having a shoulder adjacent its inner end, the intermediate portion of the lower member being curved and extending across said upper member and terminating in a laterally disposed upper jaw in alignment with the lower jaw, a link connection pivotally secured to said members, and yieldable means confined between and connected to said link connection and said shoulder for normally maintaining the jaws in their closed 110 position. 115

6. A tool of the class described including upper and lower clamping members, the upper member having a handle portion at one end and an inclined arm terminating in a laterally disposed lower jaw, said lower member being shorter than the upper member and having a shoulder adjacent its inner end, the intermediate portion of the lower member being curved and extending across said upper member and terminating in a laterally disposed upper jaw in alignment with the lower jaw, a link connection pivotally secured to said members, yieldable means confined between and connected to said link connection and said shoulder for normally maintaining the jaws in their closed position, and means on the lower member for permitting the actuation of the jaws by the thumb of the operator. 120
